His Attorney.

UNITED STATES PATENT OFFICE

REGINALD G. STANDERWICK, OF MARBLEHEAD, MASSACHUSETTS, ASSIGNOR TO
GENERAL ELECTRIC COMPANY, A CORPORATION OF NEW YORK

GOVERNING MECHANISM FOR TURBINE-DRIVEN SETS

Application filed October 19, 1929. Serial No. 400,984.

The present invention relates to turbine driven sets, and especially to governing means for such sets.

The object of my invention is to provide an improved governing mechanism for such sets, and for a consideration of what I believe to be novel and my invention, attention is directed to the accompanying description and the claims appended thereto.

One application of my invention is in connection with turbine driven centrifugal compressors, wherein the speed is governed by an operating condition other than the speed of the set, for example, the volume of fluid supplied to the compressor, the suction pressure, or the discharge pressure, and also by the speed of the set, and in the present application I have elected to illustrate specifically this application of my invention. It is to be understood, however, that this is only by way of example and that my invention is not limited thereto except where specifically so stated in the claims.

In the drawing, the figure is a diagrammatic view of a turbine driven centrifugal compressor provided with a governing mechanism embodying my invention.

Referring to the drawing, 1 indicates an elastic fluid turbine having an inlet conduit 2 and an exhaust conduit 3, and 4 indicates a centrifugal compressor having an inlet conduit 5 and a discharge conduit 6. This turbine compressor set is shown only diagrammatically and is to be taken as indicating any suitable type of turbine and of centrifugal compressor.

In conduit 2 is a valve means 7 for controlling the admission of elastic fluid to the turbine. Valve means 7 has its stem 8 connected to a piston 9 located in a cylinder 10, the piston and cylinder forming a part of a fluid actuated motor. 11 is a spring which acts on piston 9 in a direction to move it downward to effect closing of valve means 7.

Connected to the upper side of piston 9 is a stem 12 which at its upper end is pivotally connected to a floating lever 13. Connected to cylinder 10 beneath piston 9 is a pipe 14 which leads to the casing 15 of a pilot valve structure which controls the admission of ac-

tuating fluid to and from the space beneath piston 9.

In pilot valve casing 15 is a bushing or sleeve 16 which is adapted to slide in the casing and is provided with an opening 17 which communicates with pipe 14, an admission port 18 and a discharge port 19. Admission port 18 and discharge port 19 are controlled by pilot valves 20 and 21 which are connected to each other and by a suitable connection 22 to a speed governor 23. Speed governor 23 is driven through a worm gearing 24 from the shaft of the turbine, which shaft is indicated diagrammatically at 25, the connection being through a vertical driving shaft 26. Shaft 26 drives also a pump 27 which is utilized to supply actuating fluid for the control mechanism. Pump 27 may be of any suitable type, for example, it may be a gear pump. Its suction inlet is indicated at 28 and its discharge conduit is indicated at 29, the latter being provided with a suitable relief valve 29a. It is located in a tank 30 which represents the oil tank of the turbine. Pump 27 may be, for example, the pump which supplies lubricant to the turbine and compressor bearings. Connected to discharge pipe 29 is a pipe 31 which leads to the inlet port 18 of the pilot valve sleeve 16.

Pilot valve sleeve 16 is pivotally connected by a link 32 to lever 13. The right-hand end of lever 13 is pivotally connected to a rod 33, the lower end of which is connected to a piston 34 located in a cylinder 35. In cylinder 35 is a spring 36 which acts in a direction to force piston 34 downward toward the bottom of cylinder 35. Piston 34 and cylinder 35 form a part of a fluid actuated motor to which actuating fluid is supplied by a pipe 37, the flow of fluid to pipe 37 being controlled by a pilot valve structure comprising a pilot valve casing 38 in which is located the pilot valves 39 and 40. Pilot valve 39 controls the admission of actuating fluid supplied through a pipe 41, and pilot valve 40 controls the discharge of actuating fluid from pipe 37. Pilot valves 39 and 40 are connected to each other and are pivotally connected by a link 42 to a floating lever 43. The right-hand end of floating lever 43 is connected by a link 44 to

a lever 45 pivoted on a fixed support 46. The right-hand of lever 45 is connected to stem 33 whereby lever 45 may be moved by piston 34. The left-hand end of lever 43 is connected by a link 47 to a lever 48 pivoted on a fixed support 49. Connected to the left-hand end of lever 48 is a device which is responsive to an operating condition of the compressor 4. In the present instance, this device is shown as being a suction responsive device, the specific embodiment of the invention illustrated being one wherein the turbine is controlled in terms of the suction pressure. The device is shown as comprising a casing 50 in which is located an inverted bell 51, the edges of which are located in an annular chamber 52 in which is a sealing liquid 53. The under side of the bell is subjected to the pressure in the suction conduit 5 by a pipe 54. The outer side of the bell is subjected to atmospheric pressure through the opening 55. The bell 51 is connected by a stem 56 to the left-hand end of lever 48. The width of regulation of the suction responsive device, that is, the pressure change for change in load as controlled by the pressure responsive device, is controlled by an adjustable spring 57 located between lever 48 and an arm 48^a. By moving spring 57 toward the fulcrum point of lever 48 the width of regulation is narrowed, and by moving it away from the fulcrum point the width of regulation is broadened. The spring may be adjusted by means of the openings shown in lever 48 and arm 48^a. At 58 is an adjustable weight for setting the device for the desired suction pressure.

The operation is as follows:

Assume that the turbine is running and that the desired suction pressure obtains in the conduit 5. Under these circumstances, the various parts of the control mechanism will be in equilibrium, occupying the positions shown in the drawing. The admission of elastic fluid to the turbine is controlled directly by speed governor 23, which tends to hold the turbine at a certain speed. If the speed tends to increase, due to, for example, variations in driving force caused by variations in the initial pressure of the elastic fluid, variations in back pressure or variations in extraction in the case of an extraction turbine, speed governor 23 will move pilot valves 20 and 21 downward slightly, whereupon pilot valve 21 will uncover somewhat the discharge port 19, permitting fluid pressure to escape from beneath piston 9. Spring 11 will thereupon force piston 9 downward, closing somewhat the valve means 7. When piston 9 moves downward it carries with it the left-hand end of floating lever 13, thereby lowering pilot valve sleeve 16 to bring it to a position wherein port 19 is again covered by the pilot valve 21, lever 13 turning on stem 33 as a pivot. This forms a usual

arrangement of follow up connection for the fluid actuated motor. If the speed tends to decrease, pilot valves 20 and 21 are moved upward slightly, the pilot valve 20 uncovering admission port 18, whereby fluid pressure is admitted through pipe 14 to cylinder 10 beneath piston 9, raising the piston somewhat and effecting opening movement of valve means 7 to increase the admission of elastic fluid to the turbine. When piston 9 moves upward, it turns lever 13 in a direction to lift pilot valve sleeve 16 to a position wherein the admission port 18 is again covered by the pilot valve 20, thus restoring the parts to their former positions. It will thus be seen that the speed governor is in immediate control of the valve means 7 and tends to hold the speed substantially constant.

Assume now that the suction pressure in conduit 5 increases, which means that valve means 7 must be opened somewhat to increase the speed of the turbine so as to bring the suction pressure back to the desired value. The increased suction pressure acting on the under side of bell 51 moves it upward, thereby turning lever 48 on its fulcrum arm 49 and through link 47 lowering the left-hand end of lever 43; and hence the pilot valves 39 and 40. When pilot valves 39 and 40 are lowered, pilot valve 40 uncovers the discharge port in pilot valve casing 38, permitting actuating fluid to escape from the under side of piston 34. Spring 36 thereupon moves piston 34 downward, lowering the right-hand ends of levers 13 and 45. The lowering of the right-hand end of lever 13 moves pilot valve sleeve 16 downward, thus bring admission port 18 out of line with pilot valve 20 so that actuating fluid is admitted through pipe 14 to the cylinder 10 of the fluid actuated motor. Piston 9 is thereupon moved upward against the action of spring 11, opening the valve means 7 whereby the speed of the turbine will be increased. The increased turbine speed causes the weights of speed governor 23 to move outward, thereby lowering the pilot valves 20 and 21 to bring them again into line with ports 18 and 19. The turbine now operates at the increased speed, which increased speed is such as to restore the suction pressure to the desired value. When piston 9 moves upward it lifts the left-hand end of lever 13, the same turning on stem 33 as a pivot. This movement raises slightly the pilot valve sleeve 16 in a direction to restore it to its former position wherein port 18 is covered by the pilot valve 20. However, the travel of piston 9 is so small compared to the travel of piston 34 that this restoring action is negligible. The turning of lever 45 on its pivot, with the downward movement of piston 34, raises the right-hand end of lever 43, thereby restoring pilot valves 39 and 40 to their former positions, wherein

pilot valve 40 covers the discharge port of pilot valve casing 38. In case the suction pressure varies in the opposite direction, a similar operation occurs except in the opposite sense, the valve means 7 being then moved toward closed position to decrease the speed of turbine 1 and bring the suction pressure back to its normal value.

With the above described arrangement, it will be seen that the suction responsive device does not act directly on the valve means of the turbine, but acts on it indirectly through the intermediary of the pilot valve which is controlled by the speed governor. In other words, the suction responsive device operates to vary the setting of the pilot valve sleeve 16, and for every position of the pilot valve sleeve within its range of movement, there is a definite corresponding turbine speed. Valve means 7 is thus always under the direct control of its speed governor.

Heretofore, in connection with apparatus of this type, it has been the practice in regulating it to have the suction responsive device act directly on the valve gear, the speed governor being set for a speed higher than normal speed and serving as a pre-emergency governor, or to have the suction responsive device act on the synchronizing speed adjusting spring of the governor. By my improved construction, wherein the suction responsive device acts on a pilot valve sleeve, I obtain improved operating characteristics in that the governor is more sensitive, accurate and prompt. Movement of the pilot valve sleeve follows quickly any change in suction pressure and effects an immediate response in the valve gear. In addition, the pilot valve sleeve is moved immediately an amount depending upon the change in the suction pressure, whereby the governing means is enabled to follow the rate of change of the suction pressure. Also, since the suction governor or similar device acts directly on the pilot valve sleeve, the governing is more stable because a quicker action is obtained. In addition to the foregoing, important results are obtained also because disturbances in speed which may be caused by variations in initial pressure of the actuating fluid, variations in back pressure on the turbine, or, in the case of extraction turbines, variations in amounts of extracted steam, are arrested immediately by the action of the speed governor rather than allowing the speed to wander and disturb the suction pressure at the intake of the compressor. If the valve means is moved directly by the action of the suction governor or similar device, a tendency for unstable action is set up, due to the fact that considerable time must necessarily elapse for the suction pressure to change materially, and especially is this true where, as is usually the case, the capacity of the suction line is very great.

In accordance with the provisions of the patent statutes, I have described the principle of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States is:

1. In combination, a turbine driven set, valve means controlling the admission of elastic fluid to the set, a fluid actuated motor for positioning the valve means, a pilot valve structure comprising a casing, a sleeve in the casing, and a pilot valve in the sleeve, said sleeve having openings controlled by the pilot valve for controlling the supply of actuating fluid to said motor, a speed governor connected to said pilot valve, and means controlled by an operating condition of said set other than its speed for positioning said pilot valve sleeve to vary the speed of the set, the set being normally under control of said speed governor.

2. In combination, a turbine driven set, valve means controlling the admission of elastic fluid to the set, a fluid actuated motor for positioning the valve means, a pilot-valve structure comprising a casing, a sleeve in the casing, and a pilot valve in the sleeve, said sleeve having openings controlled by the pilot valve for controlling the supply of actuating fluid to said motor, a speed governor connected to said pilot valve, a fluid actuated motor connected to said sleeve, and a pilot valve controlled by an operating condition of the set other than its speed for controlling the admission of actuating fluid to said last named fluid actuated motor for positioning said sleeve to vary the speed of the set, the set being normally under control of said speed governor.

3. In combination, a turbine driven set, valve means controlling the admission of elastic fluid to the set, a fluid actuated motor for positioning the valve means, a pilot-valve structure comprising a casing, a sleeve in the casing, and a pilot valve in the sleeve, said sleeve having openings controlled by the pilot valve for controlling the supply of actuating fluid to said motor, a speed governor connected to said pilot valve, and means controlled by a pressure appurtenant to an operating condition of the driven machine for positioning said pilot valve sleeve to vary the speed of the set, the set being normally under control of said speed governor.

4. In combination, a turbine driven set, valve means controlling the admission of elastic fluid to the set, a fluid actuated motor for positioning the valve means, a pilot-valve structure comprising oppositely movable members having openings which control the

flow of actuating fluid to said fluid actuated motor, a speed governor connected to one of said members to move it in response to changes in speed for effecting adjustment of said valve means, and means controlled by an operating condition of the set other than its speed connected to the other of said members to move it in response to changes in said operating condition to effect adjustment of said valve means, the set being normally under control of said speed governor.

In witness whereof, I have hereunto set my hand this seventeenth day of October, 1929.
